(57) **CLAIM**

The ornamental design for an injection manifold, as shown and described.

DESCRIPTION

FIG. 1 is a perspective view of the injection manifold with dashed lines indicating disclaimed portions;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines shown in the drawings are for the purpose of illustrating portions of the injection manifold and form no part of the claimed design.
